UNITED STATES PATENT OFFICE.

HUGH McEWAN, OF PITTSBURGH, PENNSYLVANIA, ASSIGNOR TO WILLIAM W. NICOLL,
OF NEW YORK, N. Y.

SAFETY EXPLODER.

Application filed August 24, 1921. Serial No. 494,923.

To all whom it may concern:

Be it known that I, HUGH McEWAN, a citizen of the United States, and a resident of Pittsburgh, in the county of Allegheny and State of Pennsylvania, have invented a new and Improved Safety Exploder, of which the following is a full, clear, and exact description.

This invention relates to improvements in safety exploders, an object of the invention being to provide an exploder which will operate to detonate a cap of fulminate composition, such as commonly employed in blasting caps and which is adapted for use in connection with any ordinary form or size of cap.

A further object is to provide a safety exploder of the character described which is made and transported entirely independent of any cap or exploding fulminate and which is ready for operation at the point of blast after a cap is properly inserted therein and the exploder and cap properly located with relation to blasting and tamping material.

A further object is to provide a safety exploder which will take the place of the ordinary fuse, which will reduce danger of accidents to a minimum, which will economize blasting operations, and which can be easily and efficiently employed wherever blasting is to be done.

With these and other objects in view the invention consists in certain novel features of construction, and combinations and arrangements of parts as will be more fully hereinafter described and pointed out in the claims.

In the accompanying drawings—

Figure 1 is a view in longitudinal section illustrating my improved safety exploder with the firing pin in set position.

Figure 2 is a similar view showing the firing pin in firing position.

Figure 3 is an end view of the safety exploder with the cover in open position.

Figure 4 is a fragmentary view showing the wire for controlling the operation of the firing pin.

My improved safety exploder consists of a cylindrical tube 1 having at one end an annular flange or head 2. This flange or head 2 is provided with a cover 3 having a hinged connection at one side to the head 2, as shown at 4', and adapted to be removably

coupled to the head when in closed position. It is, of course, obvious that I might employ various means for coupling the cover and the head, but I have illustrated a simple form of snap catch or fastening means which comprises a curved tongue 4 on the cover 3, which is adapted to be forced through a slot 5 on the head 2, and by reason of the curvature of the tongue, will snap into closed position and remain in such position unless forced to open position.

Within the tube 1 I provide a firing pin 6, said pin having a relatively long needle-pointed end 7 adapted to be projected into a cap 16 illustrated by dot and dash lines in Figures 1 and 2, when said cap is in proper position in the end of tube 1 and the firing pin is operated. I believe this relatively long needle-pointed firing pin will give superior results to any other shape of firing pin.

The firing pin 6 is made with an annular enlargement 8 at a point between its ends and adjacent the inner or rear end of the firing pin 6 I provide a longitudinal slot 9 for the reception of a controlling wire 10. This controlling wire 10 at its firing pin engaging end is preferably bent at a substantial right angle as shown in Figure 4, forming a finger 11, which constitutes a safety catch, which is projected through the slot 9 and is made with an offset portion 12 located directly in the slot 9 and providing shoulders or cam faces 13 which offer resistance to the removal of the wire so as to require a considerable pull to remove the wire, and hence, prevent possibility of accidental removal of the wire which would be dangerous. Between the enlargement 8 and the finger portion 11 of wire 10 a coiled spring 14 is located around the firing pin 6 and is under compression, but cannot act

by reason of its confinement between said annular enlargement and the finger. The wire 10 passes through an opening 15 in cover 3 and is of a length sufficient to allow the wire to be carried through the tamping or embedding material after the exploder is properly set in connection with the cap and explosive material, so that a cord or other suitable flexible device may be connected to the free end of the wire and extend from any desired distance from the point of explosion, so that the wire can be pulled out of the firing pin by any one lo-

2
cated any desired distance from the point of explosion.

Normally, the wire 10 will hold the firing pin 6 against the cover 3, as shown in Figure 1, so that a cap indicated at 16 by dot and dash lines, can be inserted in the free end of the tube 1, and after the exploder and cap are properly embedded in explosive material, the device is ready for operation.

The operation is as follows: When a sufficient pull, preferably four pounds at least, is had on the wire 10 to draw the safety catch 11 of said wire out of the slot 9 of the firing pin 6, the spring 14 is free to expand and as it expands one end of the coiled spring 14 will engage the cover 3, the latter acting as an abutment for the spring and at the same time the spring will force 20 (at about one and one half pounds pressure) the firing pin into the cap, as indicated clearly in Figure 2. This operation of exploding is instantaneous with the withdrawal of the wire and the action is positive and explosion is assured because of the relatively long length of sharp needle point 7 which penetrates the cap or fulminate of the cap to insure the explosion irrespective of the size of charge or length of cap.

30 It will be noted that with my improved safety exploder, the device "is set" at the factory, as shown in Figure 1, and can be safely shipped to any point as no explosive is employed until the device is at its point of use, and furthermore, it will be noted that by reason of the offset portion 12 of the safety catch 11, danger of accidental removal of the wire is reduced to a minimum, as the wire cannot be removed except by a very appreciable pull much greater in fact than the wire could possibly be subjected to by any accidental contact and, furthermore, this safety connection between the wire and the firing pin prevents possibility

of accidental explosion during the placing 45 of the exploder in connection with the cap and blasting and tamping thereof, and will result in reducing accidents to a minimum and insuring a perfect blasting operation.

Various slight changes might be made in 50 the general form and arrangement of the parts described without departing from the invention, and hence I do not limit myself to the precise details set forth, but consider myself at liberty to make such changes and 55 alterations as fairly fall within the spirit and scope of the appended claims.

I claim:

1. An exploder of the character described, comprising a cylindrical tube, a head on one end of the tube, a cover hingedly connected to the head and adapted to be removably connected to the head so as to hold the cover against the head, a firing pin in the tube, a shoulder on the firing pin, said 65 firing pin having an opening therein, a wire projected through the cover and through the opening in the firing pin, and a coiled spring under compression on the pin interposed between the wire and the shoulder. 70

2. An exploder of the character described, comprising a cylindrical tube adapted to receive a cap in one end thereof, an annular head on one end of the tube, a cover hinged to the head, said head having a slot 75 therein, a spring tongue on said cover adapted to be projected through said slot and elastically holding the cover and head together, a firing pin in the tube having a relatively long sharp needle-pointed end, a shoulder on the firing pin, said firing pin having a slot therein, said cover having an opening therein, a wire projected through the opening in the cover and through the slot in the pin, and a coiled spring under compression on the pin between the wire and the shoulder. 85

HUGH McEWAN.
